UNITED STATES PATENT OFFICE

147,934

DESIGN FOR A CUFF LINK

Theodore F. Strub, Chicago, Ill.

Application March 27, 1947, Serial No. 137,954

Term of patent 14 years

(Cl. D17—7)

To all whom it may concern:

Be it known that I, Theodore F. Strub, a citizen of the United States, residing at Chicago, in the county of Cook and State of Illinois, have invented a new, original, and ornamental Design for Cuff Links, of which the following is a specification, reference being had to the accompanying drawing, forming part thereof.

In the drawing:

Fig. 1 is a view in side elevation of a cuff link but showing a face view of one link member and a rear view of the other and smaller member, showing my new design.

Fig. 2 is a view similar to Fig. 1 but taken from the opposite side thereof, and,

Fig. 3 is a view of the cuff link shown in Figs.

1 and 2 with the rear faces of the link members disposed directly opposite each other.

I claim:

The ornamental design for a cuff link, as shown.

THEODORE F. STRUB.
